Primary Examiner — Jeffrey D. Asch*Assistant Examiner* — Tracey J Bell(74) *Attorney, Agent, or Firm* — Banner & Witcoff, Ltd.(57) **CLAIM**

The ornamental design for a handset, as shown and described.

DESCRIPTION

FIG. 1 is a rear perspective view of a handset showing our new design;

FIG. 2 is a rear view thereof;

FIG. 3 is a right side view thereof;

FIG. 4 is a left side view thereof;

FIG. 5 is a top view thereof;

FIG. 6 is a bottom view thereof; and,

FIG. 7 is a front view thereof.

The uneven-length broken lines immediately adjacent to the shaded area represent unclaimed boundaries of the design. The even-length broken line showing of the remainder of the handset is for environmental purposes only and forms no part of the claimed design. The contrast in shading represents a contrast in surface appearance.
